E. P. HOWE.

INJECTOR.

No. 349,997.

Patented Sept. 28, 1886.

Fig. 2.

UNITED STATES PATENT OFFICE.

ELMER P. HOWE, OF BOSTON, MASSACHUSETTS.

INJECTOR.

SPECIFICATION forming part of Letters Patent No. 349,997, dated September 28, 1886.

Application filed April 28, 1886. Serial No. 200,473. (Model.)

To all whom it may concern:

Be it known that I, ELMER P. HOWE, of Boston, in the county of Suffolk, and in the State of Massachusetts, have invented certain new and useful Improvements in Injectors; and I do hereby declare that the following is a full, clear, and exact description thereof.

My invention relates to improvements in those injectors which consist of a combined 10 ejector and injector, in which the ejector is employed to supply water continuously to the injector, which forces it into the boiler whence the actuating steam is taken. It is an improvement on the injector patented by John 15 T. Hancock in Letters Patent No. 185,861, dated January 2, 1877, known as the "Inspirator."

The object of my improvement is to provide 20 simple and efficient means for rendering injectors of this class automatic both in starting and restarting whenever steam is properly supplied.

To get the inspirator described in Letters Patent No. 185,861 into operation, feeding a 25 boiler, it is necessary for the engineer to manipulate four valves in proper succession, and if for any reason its operation is stopped, three of these valves, at least, must be put back into the proper position for starting, and 30 then again successively manipulated before it will resume operation.

In my improved injector I attain the advantages of the inspirator, but dispense with all its valves which require to be manipulated 35 by the engineer, except that which admits and cuts off the admission of steam from the boiler.

For convenience I will hereinafter call the 40 ejector apparatus the "lifter" and the injector apparatus the "forcer."

In the drawings, Figure 1 is a vertical section on a plane which passes through the axes of the respective combining-tubes of the lifter and the forcer, the overflow-valves (to be described hereinafter) being shown in elevation. Fig. 2 is a transverse section on line A B of Fig. 1. Fig. 3 is a transverse section on line C D, Fig. 1. Fig. 4 is a transverse section on line E F, Fig. 1. Fig. 5 is a transverse section on line G H, Fig. 1.

Z is the casing.

J is the pipe for admission of the actuating-steam, in which pipe should be placed a valve to admit or cut off the flow of steam.

I is the water-supply pipe, which communicates with the reservoir or well. 55

L is the delivery-pipe, which leads to the boiler, in which should be placed the usual check-valve to prevent the outflow of water from the boiler. 60

K is the intermediate chamber formed in the casing, which is a conduit leading to the mouth of the combining-tube of the forcer and also, by a passage, K', to the waste-chamber O.

M is a conduit which leads from the overflow-chamber of the forcer to the waste-chamber O. The waste-chamber O partially surrounds the conduit M and communicates with the atmosphere when the valve R, which opens outwardly, is open. It is separated from the 70 conduit K' by a wall, N, formed in the casing. (Shown in section in Figs. 3 and 4 and by dotted lines in Fig. 1.)

P is a valve, which opens inwardly, and opens or closes communication between the 75 intermediate chamber, K K', and the waste-chamber O.

Q is a valve opening outwardly, which opens or closes communication between the overflow-chamber M of the forcer and the waste-chamber O. 80

a is the steam-nozzle of the lifter, which is held in position in the casing by a binding-ring, a'.

b is the combining-tube of the lifter, which is 85 screwed into the casing in axial line with the nozzle a, so that its inlet end or mouth is in the water-supply conduit I and its discharge end is in the intermediate chamber, K.

c is the steam-nozzle of the forcer, which is 90 held in position by the binding-ring c'.

d is the combining-tube of the forcer, which is screwed into the casing in axial line with its steam-nozzle c. It passes through the overflow-chamber M, and by a steam and water 95 tight joint through the casing into delivery-pipe L. Its inlet end is in the intermediate chamber, K, and its discharge end is in the delivery-pipe L. e and f are lateral openings from the forcer combining-tube into the forcer overflow-chamber M. The tubes a and b, when provided with the waste-opening to the at- 100

mosphere which is furnished by the conduit K K' when the valve P is open, are to be of the proper proportions, and arranged relatively to each other, so as to constitute an effective lifter or ejector. The tubes c and d are to be properly proportioned and arranged relatively to each other to constitute a forcing injector of the class known as "restarting" injectors having two series of relief-openings, e and f, into its overflow-chamber, the openings e, here shown as four in number, being located in the combining-tube, where the area of the cross-section of the combining-tube is greater than the smallest area in cross-section of the steam-nozzle c, the total area of the holes e being also in excess of the smallest area in cross-section of the steam-nozzle. The openings f, located near the throat of the combining-tube, correspond to the "leap across" or relief-opening of the original Giffard injector. The area of the under surface of the valve Q is considerably in excess of the area of the upper surface of the valve P. The stem Q' of the valve Q extends into the overflow-chamber O, so that when the valves Q and P are both seated, it will be almost in contact with the similarly-projecting stem P' on the under side of the valve P. The valve Q has a bevelled seat, and is also provided with a piston-30 extension, Q², fitted loosely in the upper end of the chamber M, the object of which is to compel the valve to move a much greater distance than that which separates the stems P' Q' in order to insure the valve P being wide open whenever the valve Q is open.

The valve R, to prevent influx of air to the instrument, is supported against its seat by a very light spring. It is only of importance when a partial vacuum exists in the chamber 40 K after the injector is in full operation.

The operation is as follows: Steam being admitted through pipe J, issues through the lifter steam-nozzle a and also through the force steam-nozzle b. That which issues from the lifter steam-nozzle a passes through the lifter combining-tube into the intermediate chamber, K, and the conduit K', which extends therefrom, but would be prevented from escaping into the waste-chamber O by the closed valve P, were it not that the steam which simultaneously issues from the force steam-nozzle c passes into the combining-tube d, out of the relief-openings e and f, and through the overflow-chamber M, opens the valve Q, which immediately opens wide the valve P. As the surface of the force overflow-valve Q exposed to pressure in the chamber M is greater than that of the lifter overflow-valve P, which is exposed to the pressure existing in the chamber K K', the valve P, although it is under a pressure tending to close it, must yield to the action of the valve Q and open wide, so that the steam will issue from both the valves P and Q into the waste-chamber O, and, overcoming the slight resistance of the valve R will escape into the air. The lifter is now operating in the ordinary way. The

steam which passes through it expels the air and causes the water to enter from the reservoir through the supply-pipe I and into the lifter combining-tube, whence it follows the previous course of the air and steam through the intermediate chamber, K, the conduit K', into the waste-chamber O, and out to the air through the valve R. As soon as the water 70 introduced into the intermediate chamber, K, by the lifter reaches the inlet end of the force combining-tube, a portion of it will flow into the force combining-tube to fill the partial vacuum created by the action of the steam issuing from the nozzle c and escaping at the relief-openings e and f. This water is at first 75 expelled from the openings e and f into the overflow-chamber M, whence it escapes to the air through the valve Q, chamber O, and valve 80 R. The action of the force is thereafter the same as that of any single restarting forcing-injector. The velocity of the water in the tube d is accelerated so that it leaps across the openings e and for an instant spills at f until 85 its velocity is so increased that it leaps across the openings f and enters the diverging part of the tube d, and finally enters the boiler. As soon, however, as the jet is thus established, the spill into the overflow-chamber M, 90 if any, becomes so slight that the pressure in that chamber is lessened, and usually a partial vacuum will be found therein. When this occurs, the valve Q immediately seats and 95 prevents the influx of air. The valve P, which has hitherto been held open by the excess of pressure on the under side of the valve Q, will immediately close if there is any pressure 100 in the intermediate chamber, K, and all the water discharged from the lifter will thereafter, while the instrument is in operation, be delivered through the force combining-tube. The instrument will now operate precisely as does the inspirator, and the lifter, 105 if properly proportioned relatively to the force, will deliver the water to the force in quantity equal to what the latter requires over a wide range of pressure of the actuating-steam. The pressure in the intermediate chamber, K, will decrease or increase with 110 the decrease or increase in the pressure of the actuating-steam, and consequently a less or greater quantity of water will be supplied to the force. In case of a "break"—that is, the 115 cessation of feeding to the boiler—steam again enters both the intermediate chamber, K, and the force overflow-chamber M. The valves P and Q are again automatically opened, as before described, and held open until the jet is 120 established in the force, when the valves automatically close and the instrument is in 125 full operation. Thus the operation will continue, merely admitting the actuating-steam sufficient to automatically start, and, in case of momentary cessation, to automatically restart and maintain the proper action so long as the steam is supplied. The instrument will, 130 at times when the steam-pressure is high, fail to start. In such cases it can be readily start-

ed, as can the ordinary Hancock inspirator, by throttling the steam-supply valve in the pipe J until the water is lifted and the jet established, after which the valve may be fully 5 opened. The quantity of water delivered may at all pressures be varied by manipulating the steam-supply valve in the pipe J.

Instead of the form of forcer shown and described, any one of the several forms of restarting forcing-injectors may be substituted by making proper changes in the casing. It is only essential that the relief openings corresponding to e and f should communicate with the overflow-chamber M, and this whether 15 the opening corresponding to e is obtained by making the combining-tube in sections, and sliding or swinging one section away from another, or however such relief-opening is attained.

20 It is not essential to the successful operation of the machine that the under surface of the forcer overflow-valve Q should be in excess of the upper surface of P, for I have found by experiment that the machine will start and 25 restart when these proportions are reversed; but I prefer the construction shown in the drawings, as it insures certainty of action, even if from any cause the pressures in the chambers M and K are equal.

30 I claim as my invention—

1. An injector which contains a restarting-forcer, provided with an overflow-valve to prevent the indraft of air into its overflow-chamber, and which contains, also, a lifter which 35 continuously supplies water to the forcer, and is provided with a valve on its overflow-chamber when the overflow-valves are arranged relatively to each other, as described, so that when the forcer overflow-valve is opened the 40 lifter overflow-valve shall also be open, substantially as and for the purpose described.

2. An injector which contains a restarting-forcer provided with an overflow-chamber, M,

and a lifter which continuously supplies water thereto, provided with a valve on its overflow-conduit K', adapted to be closed by pressure within that conduit, and to be opened by pressure in the overflow-chamber of the forcer, substantially as and for the purpose specified. 45

3. An injector which contains a restarting-forcer provided with an overflow-valve, Q, having a piston-extension, Q², and which contains, also, a lifter which continuously supplies water to the forcer, and is provided with a valve on its overflow-chamber when the overflow-valves are arranged relatively to each other, as described, so that whenever the forcer overflow-valve is opened the lifter overflow-valve shall be held wide open, substantially as and for the purpose described. 50

4. An injector which contains a forcer having relief-openings e and f and overflow-chamber M, into which the openings e and f lead, a lifter which continuously supplies water to the forcer, the intermediate chamber, K, the 65 common overflow-chamber O, and valves P and Q on opposite sides of the chamber O, operating automatically to open and close both overflows, substantially as described, and for the purpose specified. 60

5. An injector which contains a restarting-forcer provided with an overflow-valve, Q, and a lifter which continuously supplies water to the forcer provided with an overflow-valve, P, the forcer and lifter being arranged relatively 75 to each other, as described, and the valve R, opening outwardly from the chamber O, substantially as and for the purpose described.

In testimony that I claim the foregoing I have hereunto set my hand this 19th day of April, A. D. 1886. 80
